COMBINED REMOTE CONTROL UNIT AND SPEAKER FOR AN AUTOMATIC PHONO- GRAPH

Mahlon W. Kenney, Oak Park, Ill., and Carl W. Sundberg,
Bloomfield Hills, Mich., assignors to The Seeburg Cor-
poration, Chicago, Ill.

Filed Nov. 2, 1962, Ser. No. 72,349

Term of patent 14 years

(Cl. D56—4)

The figure is a perspective view of a combined remote control unit and speaker for an automatic phonograph, showing our new design.

The rear and bottom of the unit are plain and unornamented, and the undisclosed right hand side of the unit is substantially the same as the left hand side shown.

The dominant features of our design reside in the portions shown in full lines.

We claim:

The ornamental design for a combined remote control unit and speaker for an automatic phonograph, substantially as shown and described.
